His Attorney.

UNITED STATES PATENT OFFICE.

HARRY C. ODENKIRK, OF CLEVELAND, OHIO.

METALLIC RAILWAY CROSSTIE.

1,405,556.

Specification of Letters Patent. Patented Feb. 7, 1922.

Application filed June 13, 1921. Serial No. 477,164.

To all whom it may concern:

Be it known that I, HARRY C. ODENKIRK, a citizen of the United States, residing at Cleveland, in the county of Cuyahoga and 5 State of Ohio, have invented certain new and useful Improvements in Metallic Railway Crossties, of which the following is a specification.

This invention relates to the construction 10 of metallic railway crossties and means for firmly securing the track rails in proper position on the ties of steam and electric railways, whereby the use of the ordinary fastening spikes now commonly employed 15 are entirely dispensed with.

The prime object of the invention is to provide a simple, durable, economical and efficient metal railway tie and rail fastening means including sufficient strength to 20 successfully withstand all the trains to which the tie and rail fastening means are ordinarily subjected when in service and which are so constructed as to materially increase the longevity thereof.

25 Another object of this invention is to so construct my novel tie and rail fastening means that the number of parts employed is reduced to a minimum while the maximum amount of strength is maintained.

30 Further objects of the invention are to so construct my improved railway tie that the number of ties required per mile of road bed is materially reduced; that the track rail seat and rail securing members are rigidly 35 and securely fastened to the tie member at each side thereof with the lower surface of each of said members resting in contact with the road bed or ballast, thereby furnishing the required resiliency; that the waste of 40 material in construction is eliminated by placing the load carrying capacity under and near the rail, which materially lessens the expense; that the rail seat members are provided with track rail securing means, 45 such as hereinafter described, so that use of the spike or bolt securing means ordinarily employed is successfully avoided, and the outer ends and sides of the tie member and rail seat members, as well as the inner edges 50 of the rail seat members between said members are so buried in the road bed and ballast as to prevent any tendency of the side or endwise skidding of the ties when subjected to the excessive strains to which they 55 are naturally subjected.

The foregoing and such other objects as

may appear from the ensuing description, are accomplished by the means hereinafter more fully described, and by the construction, arrangement, location and combination of the parts such as illustrated in the accompanying drawings and particularly set forth in the claims appended hereto, it being understood that slight changes in the proportions and minor details of the construction may be resorted to without departing from the spirit or sacrificing any of the advantages of the invention.

Reference now being had to the accompanying drawings which form a part of this 70 specification it will be seen that:

Figure 1 is a perspective of the novel railway crosstie embodying my invention.

Figure 2 is a side elevation of the crosstie showing the track rails in cross-section.

Figure 3 is a longitudinal section taken through one of the rail seat and rail securing members, showing the tie member broken away and the track rail in cross-section.

Figure 4 is an end view showing the track 80 rail in side elevation, and

Figure 5 is a plan view of a portion of one of the rail seat and rail securing members.

Similar numerals of reference are employed to designate like parts throughout 85 the several figures of the drawings.

In the embodiment of my invention as illustrated I provide a tie member 1 preferably formed from a single straight upright bar of rolled steel of suitable or desirable 90 dimensions throughout its length and breadth, and at each end portion of said member and at each side thereof, is firmly and securely fastened by a plurality of riveted bolts 2 a rolled steel right angle bar or plate 3, adapted to contact with and 95 clamp against the outer faces of the tie member from its top to the bottom, each bar or plate 3 extending to the outer end of the tie member and a suitable distance laterally 100 therefrom, as well as inwardly between the track rails 4, said bars or plates 3 forming a widened bearing surface or seat for the base of each track rail. From the upper portion of each bar or plate 3 is stamped or punched upwardly and outwardly a plurality of rail securing projections 5 leaving openings 6 therethrough, said openings being covered by the base of the track rails when resting thereon, said projections 5 being adapted to 110 be forced, pressed or bent over the edges of the track rail into contact with the upper

surface of its base, at each side thereof, by a sledge or other suitable tool, thereby locking and securing the track rails to the cross-tie.

5 When it is desired to remove the tie for any purpose it can be readily performed by bending or forcing the securing projections 5 upwardly and away from contact with the rail base by the use of the well known pinch 10 bar, as will be readily understood.

It will be perceived that each angle bar or plate 3 projects laterally a considerable distance from each side of the tie member 1 thereby forming a widened tie and rail 15 seat, thus the number of ties usually employed per mile of road bed may be materially reduced and the expense considerably lessened.

It will be evident that since the railway 20 crosstie is embedded within the road bed and ballast with the laterally projecting lower surface of each angle bar or plate resting thereon, the desired resiliency will be furnished during the passage of the rolling 25 stock over the track rails, and at the same time the edges, and sides of the tie member and angle bars or plates between the rails, and the outer edges of the tie being buried within the road bed and ballast serve to 30 resist any tendency of the ties to shift sideways or endwise when subjected to the excessive strain of the rolling stock.

While I have shown the angle bars or plates 3 riveted to the tie member, it will be understood that said bars or plates may be readily secured to said member by the use of bolts and securing nuts, so that a new 35 bar or plate may be substituted if desired, or required at little expense, and without requiring an entirely new crosstie.

Having thus described my invention what I claim and desire to secure by Letters Patent is:

1. A railway tie comprising an upright 45 central tie member, a right angle bar or plate rigidly secured at each end portion of the tie member and extending from the top to the bottom of said member and to each outer end thereof, and a plurality of rail 50 securing projections struck up from each of said bars or plates.

2. A railway tie comprising an upright central steel tie member, a plurality of right

angle bars or plates secured at each end portion of said member, said bars or plates 55 extending from the top to the bottom of the member and to each outer end thereof, and a plurality of rail securing projections struck up from each of the bars or plates.

3. A railway tie comprising an upright 60 central member, a right angle bar or plate secured to each side of said member, and at each end thereof, each of said bars or plates extending laterally from the member, and a plurality of rail securing projections 65 struck up from each of the bars or plates and bent over the upper surface of the rail base.

4. A railway tie comprising an upright 70 central steel member, a right angle steel bar or plate secured to each side of the member near its ends and overlapping each side from the top to the bottom of said member and extending to its outer ends, each angle bar extended laterally beneath the rail, and a plurality of rail securing projections 75 struck up from each bar and adapted to be forced over into contact with the upper surface of the rail base.

5. A railway tie of the character described comprising a central upright member, a 80 plurality of angle bars or plates rigidly secured at each end portion of said member, each angle bar extending from the top to the bottom of the member and projecting a suitable distance laterally from the member beneath the rail base, and a plurality of upwardly extended projections struck up from each angle bar adapted to be bent over the edges of the track rail into contact with its upper surface.

6. A railway tie of the character described comprising a central upright steel member, a plurality of angle bars or plates firmly secured to the side of said member at each end portion thereof and extending to its 95 ends, each angle bar extending laterally a suitable distance from the member and from its top to its bottom edges and beneath the rail base, a plurality of rail locking projections struck up from each angle bar leaving openings therethrough adapted to be covered by the rail base, said projections being forced over the edges of the rail base and into contact with the upper surface of said base.

HARRY C. ODENKIRK.
